UNITED STATES PATENT OFFICE.

JOSEPH PENO, OF OSWEGO, NEW YORK.

WORK-BENCH CLAMP.

SPECIFICATION forming part of Letters Patent No. 756,137, dated March 29, 1904.

Application filed September 4, 1903. Serial No. 171,979. (No model.)

To all whom it may concern:

Be it known that I, JOSEPH PENO, a citizen of the United States, residing at Oswego, in the county of Oswego and State of New York, have 5 invented certain new and useful Improvements in Work-Bench Clamps; and I do hereby declare the following to be a full, clear, and exact description of the invention, such as will enable others skilled in the art to which it applies 10 pertains to make and use the same.

The invention relates to an improvement in clamps for work-benches, and resides in the production of a simple inexpensive clamp designed for adjustable connection with the 15 bench in a manner to permit its ready removal when not desired for use.

The preferred embodiment of my invention is illustrated in the accompanying drawings, in which—

20 Figure 1 is a perspective view showing the clamp in use. Fig. 2 is a plan view showing a modified locking means for the clamp. Fig. 3 is a longitudinal section on line *xx*, Fig. 1. Fig. 4 is an end view of the parts as shown in 25 Fig. 2. Fig. 5 is a section on line *yy*, Fig. 2.

Referring to the accompanying drawings, 1 represents a work-bench, in a recess 2 of which I secure my clamp-track 3, the latter being preferably of metal and secured in the 30 recess in any desired manner, preferably, however, so that its upper edge is flush with the surface of the work-bench.

My improved clamp comprises a base-plate 4, having an inturned lip 5 at the upper end 35 and a depending locking-block 6. The plate 4 is of a size to support the operating parts and in use overlies the track 3, with the block 6 resting in said track. The block is set at an angle, as shown, so that when the base-plate 40 is at right angles to the track the sharp edges of the block will contact with the opposite walls of the track. This arrangement permits the base-plate to be turned slightly to one side to entirely free the block 6 from the walls of the track, when lengthwise adjustment of the plate or its ready removal 45 from the track may be accomplished.

7 represents what I term the "gripping-plate," being pivoted at 8 to the base-plate

and having its upper edge slidably held beneath the lip 5, as shown. The upper lateral edge of plate 7 projects beyond the edge of the base-plate and is formed with teeth 9, designed to enter and hold the material to be worked in the usual manner. The lower lateral edge of plate 7 overlies the track 3 and projects beyond the edge of base-plate 4, said projecting portion being provided with a depending lug or post 10, normally within the track and contiguous one wall, as shown in 60 dotted lines in Fig. 1.

11 represents a handle eccentrically pivoted at 12 to the base-plate and designed in operation to bear against the gripping-plate 7. The movement of the handle toward locking 65 position (shown in Fig. 1) moves the upper portion of the gripping-plate toward the right, forcing the teeth 9 into the material and at the same time forces the lower portion of the plate 7 toward the left, forcing the lug 10 into 70 binding contact with one wall of the track, and consequently forcing the upper or top edge of block 6 into contact with the opposite wall of the track, thus securely locking the clamp in position. A reverse movement of the handle 75 loosens the parts and permits the lengthwise adjustment of the clamp or its removal, as desired.

In holding large and heavy material it may be found desirable to provide the clamp with 80 additional locking means, and therefore I can provide, as shown in Figs. 2 and 3, a second lock, comprising a disk 13, eccentrically pivoted to one end of block 6 and having a handle 14 projecting beyond the track. Moving 85 the handle downward will force the disk into binding engagement with the track, operating to hold the clamp in addition to the locking means above described.

If desired, my clamp can be used in connection with the form of bench-dog illustrated in Fig. 5, in which 15 represents a nut or base-block seated flush in the work-bench and formed with a central threaded opening 16. The dog proper comprises a plate 17, having 95 the usual holding-teeth 18 on opposite sides, fixed to a depending threaded stud 19, designed for engagement with the opening 16.

The dog of my construction is readily adjustable in a vertical direction and may be quickly removed when desired.

It will be noted that two sides of the dog proper are plain—that is, without teeth—by which provision is made to hold wood or other material without marring the edge, as is desirable in fine cabinet-work and repairing. If desired, means can be provided to rest between the teeth 9 and the work to prevent marring of the work by the teeth.

It will be noted that my clamp is readily placed in position in the track or other suitable guide or slide way when desired, may be quickly and conveniently adjusted as needed, and is readily removable.

The track, guide, or slide way can be formed of any suitable cross-sectional shape or form and can be arranged wherever my clamp is adapted for application, and it is evident that various modifications might be resorted to without departing from the spirit and scope of my invention, and hence I do not wish to limit my invention to the exact showing herein.

Having thus described my invention, what I claim is—

1. A support having a guide or a slide way, in combination with a clamp extending into and normally free to move along said way and carrying and provided with a swinging movable gripping member, and member-actuating and locking-lever means carried by and movable with said clamp to advance said gripping member to gripping position and simultaneously lock the clamp in the way.

2. A support having a guide or slide way, in combination with a clamp normally free to move along said way and comprising a base overlapping and having a portion extending into said way and an independently-movable gripping member carried by said base and having a portion in said way, and means independently mounted on and carried by said base to advance said member to gripping position and to lock the same in said position.

3. In combination with a work-bench having a depressed track, of a bench-clamp comprising a base-plate overlying the track and having a block depending in the track, a gripping-plate pivoted to the base-plate and having a stud depending in the track, and means to move the gripping-plate to bind the stud and block against opposite walls of the track.

4. In combination with a work-bench having a depressed track, of a bench-clamp comprising a base-plate overlying and having a block depending in the track, a gripping-plate pivoted to the base-plate and having a stud depending in the track and a handle to move the gripping-plate to bind the stud and block against opposite walls of the track.

5. In combination with a work-bench having a depressed track, of a clamp having a block depending in the track, a gripping-plate

having a stud depending in the track, means to move the gripping-plate to bind the stud and block against opposite walls of the track, and means carried by the block operative to impinge one wall of the track.

6. In combination with a work-bench having a depressed track, of a clamp having a block depending in the track, a gripping-plate having a stud depending in the track, means to move the gripping-plate to bind the stud and block against opposite walls of the track, and an eccentric disk carried by the block and movable to impinge one wall of the track.

7. In combination with a support having a depressed track, of a base-plate overlying said track and having a block depending in the track, a gripping-plate pivoted to the base-plate and having a stud depending in the track, said gripping-plate being formed with a series of gripping-teeth, and means to advance the gripping-teeth and simultaneously bind the block and stud against the walls of the track.

8. In combination with a support having a depressed track, of a clamp arranged for co-operation with said track and comprising a base-plate overlying the track and having a block depending in the track, said base-plate having an inturned lip at one end, a gripping-plate having a series of gripping-teeth, said gripping-plate being pivoted to the base-plate with its upper end slidably held beneath the lip thereof, a stud depending from the gripping-plate and within the track, and an eccentrically-mounted handle operative to advance the gripping-teeth and bind the block and stud against the walls of the track.

9. The combination with a support having a depressed track, of a bench-clamp having a rectangular block depending in the track, said block being angularly disposed with relation to the plane of the track to cause its diagonal edges to rest in proximity to the opposite walls of the track, a gripping-plate having a stud depending in the track, and means to bind the stud and diagonal edges of the block against the walls of the track.

10. The combination with a support having a depressed track, of a bench-clamp having a rectangular block depending in the track, said block being angularly disposed with relation to the plane of the track to cause its diagonal edges to rest in proximity to the opposite walls of the track, a gripping-plate having a stud depending in the track, and a handle operative to bind the stud and diagonal edges of the block against the walls of the track.

11. A bench-clamp comprising a base-plate, a gripping-plate formed with gripping-teeth and pivoted to the base-plate, said base-plate being formed with an inturned lip beneath which the gripping-plate is slidably held, a handle for forcing the gripping-plate forward, and means to secure the clamp in fixed position in the operation of the handle.

12. A support having a guide or slide way,

in combination with a clamp overlying and normally movable along and removable from said way and comprising a base, a movable gripping member carried thereby, and means comprising an independently-mounted cam locking-lever to advance said member to gripping position and simultaneously lock the clamp in said way.

13. A support having a slide or guide way, in combination with a base-plate movable along the same, a swinging gripping member mounted on and normally movable independently of said base-plate, means to lock the base-plate in said way, and an independently-mounted movable handle for advancing the gripping member on the base-plate and for locking the base-plate in said way.

14. A clamp comprising a base-plate, a swinging gripping member arranged thereon and pivoted thereto, a cam lever or handle pivoted to said base-plate for advancing said member to and locking the same in gripping position and base-plate-locking means actuated by the movement of said handle.

15. A support having a guideway in combination with a clamp overlying said way and normally free to move along the same and

provided with a movable gripping member mounted on the same, and an independently-mounted cam-lever to engage said member and carried by and movable with said clamp to advance said member to gripping position and simultaneously lock said clamp in said way.

16. A removable bench-clamp comprising a base-plate, a gripping-plate fulcrumed thereto and swinging thereon, a cam handle or lever fulcrumed to and swinging on said base-plate to engage the rear edge of said gripping-plate and force the same to and lock the same in gripping position.

17. A removable bench-clamp comprising a base-plate, a transversely-swinging gripping member fulcrumed to said plate, a cam handle or lever fulcrumed on said plate at the rear of said member to engage the edge thereof and move the same to and lock the same in gripping position, and means to secure the clamp in fixed position on the bench.

In testimony whereof I affix my signature in presence of two witnesses.

JOSEPH PENO.
